FLAME PRODUCING MECHANISM

Louis V. Aronson, Newark, N. J., assignor to Art Metal Works, Inc., a corporation of New Jersey

Application October 25, 1934, Serial No. 749,903

15 Claims. (Cl. 67—4.1)

My invention relates to flame-producing mechanism of the type embodying pyrophoric means for producing sparks which ignite the fuel.

5 My invention relates to novel mechanism of the character stated which may effectively be operated by a manual act to ignite a charge of fuel disposed at the end of a wand, torch-forming member or the like.

10 Various other objects, advantages and characteristics of my invention will become apparent from the following detailed description.

15 My invention resides in the flame-producing mechanism, features, combinations and arrangements of the character hereinafter described and claimed.

For an understanding of my invention and for an illustration of one of the many forms thereof, reference is to be had to the accompanying drawings, in which:

20 Figure 1 is an elevational view of flame-producing mechanism as constructed in accordance with my invention;

25 Fig. 2 is an elevational view showing the mechanism with the torch-forming member in operative position;

Fig. 3 is a plan view of the mechanism shown in Fig. 1;

30 Fig. 4 is an enlarged, vertical sectional view, partly in elevation, of the mechanism shown in Fig. 1;

35 Fig. 5 is a vertical sectional view, partly in elevation, showing the parts in an operated relation;

Fig. 6 is a vertical sectional view, partly in elevation, and is taken on the line 6—6 of Fig. 3 looking in the direction of the arrows; and

Fig. 7 is a perspective view of a part of the operating mechanism shown in Figs. 3 and 4.

Referring particularly to Fig. 4, 1 represents a 40 casing wall which, preferably, defines a circular chamber although, obviously, said chamber may be of any other suitable configuration. As illustrated, the wall 1 is embraced by a lower skirt section which may be formed from members 2 and 3 suitably secured to each other and to said wall 1. Preferably, the interior space defined by the members 2 and 3 is partially or entirely filled by suitable heavy material such as lead, solder or the like, not shown.

45 Disposed interiorly and suitably secured to the interior surface of the casing wall 1 are a pair of spaced walls 4 and 5 which, together with the enclosed section of said wall 1, define a fuel casing adapted to receive a supply of high test 50 gasoline or other suitable fuel. Such fuel may

be introduced into said fuel casing upon removal of a closure cap 6 which may be threaded into an opening formed in the lower wall 5 and, preferably, the fuel casing contains a mass 7 of cotton or similar material utilizable for absorbing the 5 fuel.

As shown in Fig. 4, the upper wall 4, adjacent the periphery thereof, is provided with an internally threaded passage 8 which receives the externally threaded section 9a of a tubular member 9, the lower section of which depends into the aforesaid fuel casing, said lower tubular section being provided with one or more apertures or slots 9b. The tubular member 9 extends upwardly through an opening provided in the top 15 wall 10 of the casing 1, the upper section of said member 9 having an encircling sleeve 11 threaded thereto whereby it is firmly anchored in position.

Extending through the fuel casing is a tubular member 12 which is open at both ends and 20 suitably secured to the top and bottom walls 4 and 5 of said fuel casing, the member 12 being disposed vertically and the longitudinal axis thereof preferably being disposed substantially in alignment with the longitudinal axis of the 25 casing 1 which, in the example shown, defines a circular chamber.

The upper end of the tubular member 12 is shaped to form a seat 12a for the bevelled surface 13a of a tubular standard 13, the lower section of which extends downwardly interiorly of the tubular member 12. A nut 14, threaded to the extreme lower end of the standard 13, is adapted to coat with the bottom casing wall 5 whereby the bevelled surface 13a is held in engagement with the seat 12a to thereby securely anchor the standard 13 in upright position.

35 A tubular member 15 is disposed, in freely slideable relation, interiorly of the standard 13, this member being biased in an upward direction by a helical spring 16a which is disposed interiorly of the standard 13 and said member 15 in the manner shown in Fig. 4. The member 15 comprises an upper stem 15a which terminates above the top wall 16 of a casing 17, the extreme upper 40 end of said stem 15a having a pinion 18 fixed thereto so as to be immovable with respect thereto. Loosely disposed on the stem 15a is a sleeve 19 which has a spiral slot 19a formed in the circular wall thereof in the manner clearly 45 shown in Figs. 4 and 5. This sleeve 19 should be immovably secured to the top casing wall 16 or, preferably and as shown, said sleeve 19 may be formed integrally with said casing wall 16. The stem 15a is provided with a slot 15b, Fig. 7, 50

and, through this slot, extends a bolt or member 20 which is anchored transversely in the upper end of the standard 13, said member 20 also extending through the slot 19a. In order that the 5 operation may be effected as hereinafter described, the top casing wall 16 is provided with a passage 16a of larger diameter than that of the casing 17 so that the latter may be reciprocated freely in a vertical direction.

10 Supported on the casing wall 16 is an abutment 21 which comprises an extension arm 21a adapted to receive one end of a vertical member 22 supported at its other end in said casing wall 16. Freely rotatable on the member 22 is a 15 pinion 23 which meshes with the aforesaid pinion 18 of the stem 15a. The pinion 23 comprises an upper circular ratchet section 24 which meshes with a corresponding circular ratchet section 25 formed on the lower side of a hub 26 loosely journaled on the member 22. The pinion 23 is suitably biased in an upward direction, as by a spring 27 coiled around the member 22, so that the ratchet section 24 of said pinion 23 releasably engages the ratchet section 25 of the hub 26.

20 25 The hub 26 has a serrated wheel 28 secured thereto so as to be movable therewith as a unit. Coactable with this serrated wheel 28 is a pyrophoric element 29 which is biased into engagement therewith in any suitable manner. In 30 accordance with a preferred form of the invention, there is utilized for this purpose an arm 30 which is pivoted on a member 31 upstanding from the casing wall 16, a spring 32 which is coiled around the hub of the arm 30 serving to 35 bias said arm in a counter-clockwise direction, Fig. 3. The end of the arm 30 is so disposed in a slot 21b formed in the abutment 21 that it engages the pyrophoric element 29. Accordingly, under the influence of the spring 32, the arm 30 40 is caused to engage the pyrophoric element 29 whereby the latter, with the desired degree of pressure, is held in engagement with the periphery of the serrated wheel 28.

The hereinbefore described tubular member 9 45 serves as a holder for a torch-forming member T which may be of any suitable character such, for example, as disclosed in my pending applications Serial No. 719,640, filed April 9, 1934 and Serial No. 727,060, filed May 23, 1934. As herein 50 illustrated, the torch-forming member T comprises an upper handle section 33 having a conical surface 34 disposed immediately therebelow. Depending from the conical surface 34 is a tubular stem 35 which receives a tubular wick member 55 37 having a rod 38 extending axially therethrough. Threaded or otherwise suitably secured to the lower end of the stem 35 is a cap member 39 which comprises a depending U-member 39a through the open passages of which, the lower 60 end of the wick 37 is exposed as clearly illustrated in Fig. 5.

Normally, the torch-forming member T is seated in the tubular member 9 as illustrated in Fig. 4. When thus seated, the conical surface 34 65 frictionally engages the interior surface at the upper end of the tubular member 9 to thereby seal the outlet from the fuel casing through said member 9. When the torch-forming member T is seated in the manner shown, the lower end 70 thereof is disposed within the fuel casing, the fuel readily passing to the exposed end of the wick 37 through the passages 9b of said member 9. In this manner, the wick 37 is charged with a supply of the fuel stored in the fuel casing. 75 If desired, the fuel casing may contain a tubular

structure 7a formed of felt or the like, this structure being disposed around the lower end of the tubular member 9 and forming a porous-wall chamber for the lower end of the torch-forming member T.

The operating parts are shown in their normal respective positions in Fig. 4. When they are to be operated, the torch-forming member T is withdrawn from the tubular member 9 and positioned as shown in Fig. 2 with the U-member 39a 10 thereof seated in the depression 15c formed in the upper end of the stem 15a. The torch-forming member T is then pressed downwardly in substantially a vertical direction to move the operating parts to the positions shown in Fig. 5. 15

When the torch-forming member T is pressed downwardly, resultant downward movement is imparted to the member 15 which moves inferiorly of the standard 13 and compresses the spring 16a. During such downward movement 20 of the member 15, the coacting slot 15b and the member 20 operate to prevent rotative movement of said member 15. Due to the described relation of the parts, the casing 17 moves downwardly with the member 15. The sleeve 19, which 25 forms an integral part of said casing 17, also moves downwardly and the spiral sleeve slot 19a coacts with the fixed member 20 to cause the casing 17 to rotate in a clockwise direction, Fig. 3. Such rotation of the casing 17 causes the pinion 30 23 to partake of a planetary motion as regards the fixed, non-rotatable pinion 18 and, accordingly, clockwise rotative movement is imparted to said pinion 23, Fig. 3. The ratchet sections 24 and 25 are in clutching relation when the pinion 35 23 moves as last described and, therefore, the above described movement of said pinion 23 causes the serrated wheel 28 to partake of clockwise rotation, Fig. 3, while moving circumferentially with respect to the center of the pinion 18. It results, therefore, that the serrated wheel 28, while partaking of similar circumferential movement, is rotated in a clockwise direction, Fig. 3, whereby, by coaction thereof with the pyrophoric element 29, a stream of sparks is produced and these pass along a diverging path extending above the depression 15c of the member 15. Inasmuch as the lower end of the torch-forming member T is positioned in this depression at this time, it results that the fuel charge 50 carried by the lower exposed surface of the wick 37 is ignited to produce a freely burning flame.

When the application of downward pressure to the member 15 is discontinued upon removal of the torch-forming member T, the spring 16a 55 expands to restore the various operating parts to the respective operating positions thereof shown in Fig. 4. In so doing, the casing 17 is caused to ascend while rotating in a counter-clockwise direction, Fig. 4, the ascent of said casing being 60 discontinued when the surface of the spiral slot 19a defining the extreme lower surface thereof comes into engagement with the fixed member 20. During such counter-clockwise rotation of the casing 17, rotative movement of the serrated wheel 28 is not effected. This wheel remains stationary at this time because the ratchet sections 24 and 25 are so disposed that they idle during such counter-clockwise rotation of the casing 17 and further by reason of the fact that 65 the pyrophoric element 29 applies a braking or restraining force to said serrated wheel 28.

After the flame at the end of the torch-forming member T has served its intended purpose, such flame may be extinguished and the member 70 75

T returned to the position thereof shown in Fig. 1. By so doing, the fuel casing is sealed from the atmosphere and an additional charge of fuel is taken up by the wick 37.

5 It will be understood that the flame produced at the end of the torch-forming member T may be used for any desired purpose, such as the ignition of candles, cigarettes, pipes, etc. An especially advantageous characteristic resides in 10 the fact that the torch-forming member T may readily be passed from hand to hand whereby a plurality of different lighting operations may be readily effected.

An important feature of my invention involves 15 the arrangement for discharging a stream of sparks toward the lower exposed end of the wick 37. These sparks are produced continuously while the casing 17 passes from its upper to its lower position and, accordingly, the desired 20 burning flame is more surely produced than would be the case if a sudden quick discharge of sparks were relied upon for performing this purpose. In other words, the spark-producing unit and the ignitable object move together as a unit during 25 the effective half-cycle of operative movement of said unit. During this entire half-cycle, sparks are being produced and these sparks, due to the great quantity thereof, necessarily perform their intended purpose.

30 It should also be noted that the spark-producing unit per se is of a novel and practical type. The arrangement involving the lever 30 and spring 32 biases the pyrophoric element into engagement with its serrated wheel with nicety and 35 precision.

It is to be distinctly understood that the invention is not to be limited to the form thereof herein disclosed. Certain characteristics of the invention such, for example, as discussed above, 40 are considered broadly new and these novel characteristics, within the scope of the invention, may be exemplified by apparatuses of widely different type from the one herein disclosed.

While the invention has been described with 45 respect to a certain particular preferred example which gives satisfactory results, it will be understood by those skilled in the art after understanding the invention, that various changes and modifications may be made without departing from the spirit and scope of the invention and it is intended therefore in the appended claims to cover all such changes and modifications.

What is claimed as new and desired to be secured by Letters Patent is:

55 1. In combination, a spark-producing device movable along a path while producing sparks, a supporting member for said device, and means for moving said device and member along said path, said means comprising a torch member adapted to be manually pressed into engagement with said supporting member.

2. In combination, a spark-producing device movable along a path while producing sparks, a supporting member for said device, means for 65 moving said device and member along said path, said means comprising a torch member adapted to be manually pressed into engagement with said supporting member, and spring means for returning said spark-producing device and supporting member to normal position after removal of said torch member.

3. In combination, a spark-producing device reciprocatory in a vertical direction, a supporting member for said device, means for depressing 70 said device and member, said means comprising

a torch member adapted to be manually pressed into engagement with said supporting member, and means for moving said device substantially circumferentially with respect to said torch member.

5 4. In combination, a spark-producing device reciprocatory in a vertical direction, a supporting member for said device, means for depressing said device and member, said means comprising a torch member adapted to be manually pressed into engagement with said supporting member, means for moving said device substantially circumferentially with respect to said torch member, and spring means for elevating said spark-producing device and supporting member to normal position after removal of said torch member, 10 said device moving in reverse circumferential direction during elevation thereof.

15 5. In combination, a standard, a spark-producing device, means for supporting said device for depression, elevation and rotation on and with respect to said standard, and means whereby sparks are produced during depression of said device.

20 6. In combination, a standard, a supporting member reciprocatory thereon, a spark-producing device carried by said member at one side of the center thereof, and means for rotating said supporting member during elevation and depression thereof, said spark producing device 25 moving circumferentially with respect to said standard during rotation of said supporting member.

25 7. In combination, a standard, a member mounted on said standard for reciprocatory movement only, a spring for normally biasing the upper section of said member above said standard, a supporting member mounted on said upper section of said first named member for rotatable movement only, and a spark-producing device 30 carried by said supporting member at one side of the center thereof so as to move circumferentially with respect to said standard during rotation of said supporting member.

35 8. In combination, a standard, a member mounted on said standard for reciprocatory movement only, a spring for normally biasing the upper section of said member above said standard, a sleeve comprising a spiral slot mounted on said upper section of said member, means carried 40 by said standard for coaction with said slot to effect rotatable movement of said sleeve, and a spark-producing device carried by said sleeve so as to move circumferentially with respect to said standard during rotation of said sleeve.

45 9. In combination, a spark-producing device, means for guiding said device along a path, and means for operating said device to produce sparks during movement thereof along said path, said operating means comprising a torch member partaking of movement with said device, said torch member, during operation of said device, being 50 positioned in the path of the sparks.

55 10. In combination, a spark-producing device, means for guiding said device along a path, and means for continuously operating said device during movement thereof along said path, said operating means comprising a torch member partaking of movement with said device, said torch member, during operation of said device, being 60 positioned in the path of the sparks.

65 11. In combination, a movable spark-producing device comprising a serrated member and a pyrophoric element, and means for operating said device to produce sparks, said means comprising 70

a torch member which, during operation of said device, is positioned in the path of the sparks, said means comprising mechanism operative to effect movement of said spark-producing device as a unit during production of the sparks.

5 12. In combination, a spark-producing device, means for guiding said device along a path, means for moving said device arcuately with respect to said path, and means for operating said 10 device to produce sparks during movement thereof along said path, said operating means comprising a torch member partaking of movement with said device, said torch member during operation of said device, being positioned in the 15 path of the sparks.

13. In combination, a supporting casing, a spark-producing device, means for guiding said casing and said device alternately in opposite directions along a path, and means for continuously operating said device during movement thereof in one direction along said path, said device remaining in non-operative condition during movement in the opposite direction along said path, said operating means comprising a torch

member partaking of movement with said device, said torch member, during operation of said device, being positioned in the path of the sparks.

14. In combination, a supporting casing, a spark-producing device, means for guiding said 5 casing and said device alternately in opposite directions along a vertical path, and means for continuously operating said device during movement thereof in one direction along said path, said device remaining in non-operative condition during 10 movement in the opposite direction along said path, said operating means comprising a torch member partaking of movement with said device, said torch member, during operation of said device, being positioned in the path of the 15 sparks.

15. In combination, a wick, a spark-producing device, means forming for said spark-producing device a path which is circularly disposed with respect to said wick, and means for moving said 20 spark-producing device along said path while projecting sparks therefrom in the direction of said wick.

LOUIS V. ARONSON
